WATSON SANFORD, OF BROOKLYN, NEW YORK.

Letters Patent No. 91,569, dated June 22, 1869.

HOT-AIR FURNACE.

The Schedule referred to in these Letters Patent and making part of the same.

all whom it may concern:

Be it known that I, WATSON SANFORD, of the city of Brooklyn, county of Kings, and State of New York, have invented certain new and useful Improvements in Hot-Air Furnaces; and do hereby declare the following to be a full, clear, and exact description thereof, reference being had to the accompanying drawings, and to the letters of reference marked thereon.

Of these drawings—

Figure 1 is a front elevation;

Figure 2 is a horizontal section, taken in the line A a of fig. 1;

Figure 3 is a cross-vertical section, taken at the line B b of fig. 2;

Figure 4 is a plan view; and

Figure 5 is a plan view of the grate on an enlarged scale.

My improvements relate to and are designed to render more efficient the furnace patented by me on the 6th day of May, 1862, their main object being to effect a better distribution, and hence a greater utilization of the products of combustion; also, to more rapidly free the body of live coals of cinders.

I propose combining with a series of side flues, which are exterior to the dome of the fire pot, and arranged vertically, or nearly so, but opening into the fire-pot horizontally, a centre feed or coal-receiver, thus permitting the flues so constructed, and with such an improved combination and arrangement of dome and centre feed, to perform their functions the better, by more perfectly heating them, the fuel being spread toward these side flues, and the gases confined within the small space formed between the centre feed and sides of the dome are the more quickly and completely forced back to the series of outside flues, thereby heating the latter to a higher degree with a less amount of fuel.

I further make this centre feed so that it can be taken off or replaced, in the manner described, without necessitating the removal of other parts at same time.

I also divide, and thereby distribute more fully the products of combustion after they have passed up the vertical side flues of the furnace, and thus, by providing for their further retention and circuitous passage, get more caloric from the same amount of fuel without increasing the number of flues, or occupying space required for the storage of hot air.

In this horizontal flue I introduce a valve or opening, with which to check or retard the passage through such flue of the products of combustion.

I also, by improving the construction of the grate, cause the cinders, as they are shook by the motion of the grate, to be caught and more thoroughly crushed, so that they pass quickly and readily to the ash pit.

I will now proceed to describe, by means of the ac-

companying drawings, these general features of my invention, the same letters of reference indicating corresponding parts in the several figures.

a a, &c., are the side flues, opening into the furnace at a point of the fire-box about where the surface of the fuel ordinarily reaches, the centre feed b supplying the fuel, thus preserving these flues, so positioned, from being rendered less efficient, as would be the case in feeding over the surface of the bed of fuel from the usual side coal-receiver c. This side receiver can be retained, however, and mainly serve as a window or door, being furnished with isinglass, through which to see the condition of the fire.

Fig. 3, of the drawings, shows, by red line, the side, in case the side receiver c is not included in the construction of the furnace, there being, in such case, an opening, provided with a door containing mica, if desired, at the point d.

The depth of this centre feed is sufficient to admit of its preserving a surface upon a bed of fuel reaching up to or a little above the lower end of the side flues.

This centre feed can be cylindrical, (as shown in the drawings,) square, or other convenient form, as may be desired, and may have a coal-receiver projecting outward and obliquely from the top, similar to c, for greater convenience in feeding.

This centre feed has a knob, or other suitable projection at e, which rests on the projection f, when the device has been inserted within the furnace; and opposite thereto is attached, to the inner side of the furnace, a button, g, which, when turned up against the projection h, on the side of the centre feed b, contiguous thereto, locks the device securely and safely in place.

h is the horizontal flue, through which are carried the products of combustion from the flues a a, &c., and may extend a portion of the way, (as shown in the drawing,) or all the way round the body of the furnace.

In this horizontal flue I am enabled to place a division-plate, i, by constructing such flue in two sections, and then bolting the sections together at intervals, (the edge of the plate being between,) as seen at j j, &c.

In the form of horizontal flue shown in the drawings, a circulation is made around this division-plate to the upper section of the flue, by leaving spaces between each end of the plate and the end plates K K.

In case the flue extends all the way round, spaces in the division-plates are left at the front, which will bring the products of combustion round to the front, and up through such spaces to the upper side of the division-plate, from which they pass back through the upper section of the flue to the aperture l of the smoke-pipe.

These end plates K K have openings in them, which form valves, for the introduction of currents of cold air.

In case of the horizontal flue extending all the way

round, such valves are to be placed at any desired or convenient point.

I place the circular grate *m* upon a swivel-pin, *n*, which is at the centre of the grate-bar, or support, *o*, the circular grate having, for some distance from this pin *n*, a circular opening, which permits of there being placed upon the bar, within this opening, two projections, or lugs, *p p*, said lugs having their longest sides facing each way of the length of the grate-bars or support, and such sides are angled, or corrugated, and the ring, or collar *q*, upon the pin *n*, and the interior of the smaller or inner circular bar *r*, of the grate, have also angled projections, or spurs upon them, so that when the grate receives a reciprocal horizontal motion, for the purpose of freeing the fire of ashes, the cinders will pass down to and become engaged with these projections, or spurs, or with the projections upon the one or the other, and be crushed to ashes, by reason of such contact and a contact with the uneven and sharp surfaces of the stationary lugs *p p* on the bar.

These lugs might be employed without the aid of the projections upon the surrounding portions of the grate with advantage.

This construction of grate can be applied, as well as the other improvements above described, to many of the heating and cooking-apparatus as well as stoves at present in use, and the application is not intended to be confined or limited to hot-air furnaces proper.

Claims.

1. A centre feed, arranged relatively to and in connection with a series of side flues and the horizontal top flue connected to the latter, when such side flues are exterior to and open horizontally into the fire-pot, substantially as described.
2. A horizontal flue or flues, constructed with a division-plate, in combination with side flues, substantially as described.
3. A horizontal flue or flues, constructed with a division plate, in combination with a valve or valves, substantially as described.
4. The arrangement, in combination with a horizontal flue or flues, constructed with a division-plate, of a valve or valves, substantially as described.
5. The centre feed *b*, attached to the dome by means of the projections *h e f*, and button *g*, in manner shown and described.
6. The arrangement of lugs, or projections upon the grate-bar support *o*, in connection with spurs, or projections upon either the inner ring of the horizontal grate, or upon the collar of the centre-pin, or both, when constructed and operating substantially as described.

WATSON SANFORD.
